United States Patent Office.

ABRAM JACKSON, OF LEBANON, TENNESSEE.

Letters Patent No. 104,595, dated June 21, 1870.

MOTIVE-POWER APPARATUS.

The Schedule referred to in these Letters Patent and making part of the same

To all whom it may concern:

Be it known that I, ABRAM JACKSON, of Lebanon, in the county of Wilson and in the State of Tennessee, have invented certain new and useful Improvements in Motive-Power; and do hereby declare that the following is a full, clear, and exact description thereof, reference being had to the accompanying drawing and to the letters of reference marked thereon.

The nature of my invention consists in the construction and general arrangement of several series of levers, arms, and weights, with a series of wheels on a common axle, for the purpose of producing motive power for turning any kind of machinery.

In order to enable others skilled in the art to which my invention appertains to make and use the same, I will now proceed to describe its construction and operation, referring to the annexed drawing, which forms a part of this specification, and in which—

Figure 1 is a side elevation in section, and

Figure 2, a plan view.

A represents the frame of the machine, on the ends of which frame the shaft B has its bearings, in suitable journal-boxes.

From each of the two ends of the frame A extend two upright standards, C and C', of unequal height.

The standards C C' are, at their upper ends, connected by a beam D, and the standards C' C' by another beam, D'.

On the shaft B is secured a series of wheels, E E', each of which has its separate and distinct group of levers, arms, &c. Each of these groups being exactly alike, I will only describe one of them; but I wish it distinctly understood that each of the wheels E works in connection with a similarly arranged group as the one now to be described.

On the rear side of the beam D, and on a line with the wheel E, is pivoted an arm, F, which hangs downward, extending to the upper edge of the frame A, that is, on a line with the shaft B. This arm, when in such position, rests against a board, G, secured near the lower ends of the standards C C', extending the whole length of the frame A.

The board G is provided with rubber bands a a', or other suitable bumpers, against which the arm F will strike when the machine is in motion.

The arm F is, at its lower end, provided with another arm, H, extending toward the rear, at right angles from the former.

The arm H is, at its outer end, provided with a box, I, or other suitable receptacle, in which heavy weights may be placed.

J is a brace connecting the arms F and H.

From a suitable point on the arm F another arm,

K, which is pivoted to the former, extends over the wheel E, resting on the same.

The arm K is provided with a hook or notch, b, on its under side, which is to catch on a projection, c, of the wheel E, in a manner and for a purpose hereinafter to be set forth.

The wheel E is provided with two of these projections c c, dividing the circumference of the wheel in two equal parts.

On the upper side of the beam D, between suitable ears, is pivoted a lever, L, which crosses said beam and extends a suitable distance in front and rear of the same.

The rear end of the lever L is, by a bar, M, connected with the arms F and H, at the joint or angle formed between them, said bar M being pivoted at both ends.

The front end of the lever L is, by means of a rod, N, which should be so constructed as to admit of expansion and contraction, connected with a bar, O, pivoted to the upper side of the beam C'.

The rod N is pivoted to the lever L, and also to the bar O, near the middle, in such a manner that when the arm F hangs downward, as above described, the bar O will incline upward from its lower end, which, as mentioned, is pivoted to the beam C'.

The inclination of the bar O is toward the rear, as well as upward, and at its upper rear end a bar, P, is pivoted, which hangs downward in front of the axle B. At the lower end of the bar P is attached a shoe, d, extending forward at right angles from the bar P.

At the rear end of the shoe d, a lever, e, is pivoted, which lever is so constructed that its own weight will cause it to rest in the shoe, its front end resting on the front part of the shoe, and its rear end extending a suitable distance in rear of the same.

The front end of the lever E is held down in its place by a trigger, f, pivoted in the front part of the shoe d above said lever.

On the frame A, in front of the wheel E, is placed a pin, h, for the purpose of operating the trigger f at the proper time, in a manner that will be hereinafter set forth.

At the front side of the frame A are secured upright bars, R R, the upper ends of which are connected by a bar, S.

On the bar S, in front of the wheel E, is placed a roller, i, on which the front end of the arm K rests.

On each side of the roller i is a guide-rod, k, to keep the arm K in its place.

If, now, each of the wheels E E', or the shaft B, is provided with such a group of levers, bars, arms, &c., as above described, and each wheel is further provided

with two pins, $m m$, placed a suitable distance from the main shaft, and on a line with the projections $c c$, that is, each pin m between the shaft and said projection; then the machine can be set to operate in the following manner:

The arm H is drawn back sufficient to allow the hook h on the arm K to catch on the projection c on the wheel E . The weight in the box I presses the arm K forward, turning the wheel E a certain distance. All the wheels $E E$ being placed solid, or secured to the shaft B , all the wheels, with the shaft, are turned a certain distance. When the arm F strikes against the board G , its arm K will cease to operate; but, at that moment, or an instant previous, the next arm K should have been in such a position as to catch on its respective wheel, and so on, continuing the motion, each wheel being operated upon in succession by its weighted arm H and arm K . When the first arm K ceases to operate, the pin m on the side of the wheel E bears down on the rear end of the lever e , said lever being held by the trigger f , which causes the weighted lever or arm H to be drawn back again through the medium of the intermediate bars P O , rod N , lever L , and bar M , until the arm K is ready to catch on the second projection of the wheel E , when the trigger f strikes the pin h , which releases the lever e from the pin m , allowing the weighted arm H to operate on its arm K and wheel E , as above described. The lever e instantly, by its own weight, falls back again in the shoe d , under the trigger f . All of the groups performing in succession the same movements, a continuous rotary motion is contributed to the shaft or axle B , so that, by connecting said axle in any manner with any kind of machinery, the said machinery may be operated. The power may be increased at will in two ways, either by increasing the weights in the boxes $I I$, or, if that is not sufficient, by increasing the number of wheels and groups on the main shaft.

Upon the end of the main shaft or axle is a cog-wheel, as shown, to which power is communicated with the axle. This may be a belt, instead of a cog or cogs, so that the axle may be operated by any known power.

It will be understood that a very small power is necessary to operate the machine, as, when thus in operation, the different groups of levers, arms, &c., operate in succession, as above described, each on its own wheel, and the rotary motion of the axle is not only continued, but increased to any degree desired.

Having thus fully described my invention, What I claim as new, and desire to secure by Letters Patent, is—

1. The arrangement of the lever L , bar M , arms F and H , weighted box I , and arm K , with its hook h , all substantially as shown and described.
2. The arrangement of the lever L , screw-rod N , bars O and P , shoe d , lever e , trigger f , and pin h , all substantially as shown and described.
3. In combination with the subject matter of first and second clauses, the wheel E , provided with projections $c c$, and pins $m m$, all substantially as and for the purposes herein set forth.
4. The combination of a series of wheels on a common axle, with a series of groups consisting of levers, bars, arms, &c., when all are constructed, arranged, and combined, as shown and described, for the purpose of increasing the rotary motion contributed to said axle, substantially as herein set forth.

In testimony that I claim the foregoing, I have hereunto set my hand this 6th day of February, 1869.

ABRAM JACKSON.
